(57) **CLAIM**

I claim the ornamental design for an adhesively-attached elastomeric shoe for hooved animals, as shown and described.

DESCRIPTION

FIG. 1 is a rear, side perspective view of the adhesively-attached elastomeric shoe for hooved animals showing my new design;

FIG. 2 is a front elevational view thereof;

FIG. 3 is a top view thereof;

FIG. 4 is a rear elevational view thereof;

FIG. 5 is a bottom view thereof; and,

FIG. 6 is a side view thereof, the opposite side view being a mirror image.
